UNITED STATES PATENT OFFICE.

EUGÈNE SCHNEIDER, OF LE CREUZOT, FRANCE.

SUBMARINE MINE.

1,136,052.

Specification of Letters Patent.

Patented Apr. 20, 1915.

Application filed December 19, 1914. Serial No. 878,080.

To all whom it may concern:

Be it known that I, EUGÈNE SCHNEIDER, a citizen of the Republic of France, residing at Le Creuzot, Saône-et-Loire, France, have 5 invented a new and useful Improvement in or Relating to Submarine Mines, which is fully set forth in the following specification.

The present invention relates to a device applicable to submarine mines in which the 10 depth of the immersion of the mine after it has been moored is determined by the length of a line or cable, secured on the one hand, to a weight or sounding-lead, and on the other hand, to a member which according to 15 20 25 30 35 40 45 50 55 60 65 70 75 80 85 90 95 100 105 110 whether the said cable is taut or slack, permits or prevents the unwinding of the cable connecting the float of the mine with its anchor. In mines of this kind, when it is desired to immerse the float at a certain depth, the length of the line of the sounding-lead must be adjusted accordingly. The length of the cable which corresponds to the maximum immersion provided for the mine, is wound around or within the sounding-lead, and it is entirely unwound when the mine is moored or anchored at its maximum depth. When it is desired, however, to anchor the mine at a lesser depth, it is necessary to prevent the unwinding of a portion of this cable. At present this result is obtained generally by winding the cable on an auxiliary winch the unwinding movement of which is stopped after a certain number of revolutions by means of various devices (this solution is complicated); or by joining a certain number of convolutions of the cable by a tie-rope or a knot. This tie-rope or knot is liable to be displaced or slip and consequently the depth of the anchorage is uncertain.

The present invention has for its object to provide a simple, reliable and rapid means for adjusting the length of the cable which is unwound at the time of anchoring, without having recourse to intermediate mechanical means and without the formation of knots at intermediate points of the length of the anchoring cable.

The invention consists principally in providing in the body of the sounding-lead, a plurality of ducts or conduits, preferably diametral, so as to render it possible to control the length of cable which will be unwound, by a simple unwinding before fixing the cable to the anchor, and by passing the end of the length which is unwound to the

desired extent, through that duct the opening of which is nearest thereto.

One embodiment of the invention is illustrated in the accompanying drawing, in 60 which:

Figure 1 is a sectional side view of the sounding-lead, the partial section being taken through the convolutions of the anchoring cable. Fig. 2 is a corresponding 65 plan. Fig. 3 is a diagram showing in sectional elevation the sounding-lead having, after its launching, unwound a length of the cable under the control of the improved device, in accordance with the desired depth of 70 immersion.

The sounding-lead 1 is formed with a circular groove 2 in which the cable 3 is wound, the end 4 of the latter being secured in a cavity of the said sounding-lead. The 75 sounding-lead is formed with a certain number of diametral ducts 5 (in the example illustrated in the drawing, three ducts are shown) which merge into the upper and lower edges of the groove 2. Any number 80 of knobs 6, six for instance, may be fixed in pairs facing each other, on either side of the groove, in suitable notches. Rubber rings 7, stretched between each pair of knobs, keep the cable wound in the groove and prevent it 85 from unwinding after it has been anchored. An eye-bolt 8 fixed to the sounding-lead permits the latter to be connected to a suitable hook carried by the mine.

The operation is as follows:—The anchoring cable being assumed to be entirely wound in the groove without passing through any of the ducts 5 and that end by which the cable is secured to the anchor being assumed to be free so as to control the immersion 90 of the mine to the desired depth, the corresponding length of cable plus the length of the duct 5 is unwound from the sounding-lead; this length is measured on the cable, then the free end of the latter 100 is passed through that duct 5 the opening of which is nearest to the point fixed on the cable. The desired length of cable thus unwound from the sounding-lead is again wound in the groove 2 and the whole is 105 maintained in position by means of the rings or bracelets 7. The free end is secured to the member 9 of the mine which determines the extent of unwinding of the cable connecting the float to the anchor. The 110 sounding-lead is secured by means of its eye-bolt 8 to a suitable hook fixed on the

mine. At the time of anchoring, the sounding-lead is unhooked, the tension of the cable breaks the rubber rings 7, and the cable is unwound from the groove 2 up to the 5 point where it enters the duct 5 (Fig. 3). From this moment onward the unwinding action of the cable is stopped and the unwound length is that which is determined by the distance a between the point where 10 the cable leaves the duct 5 and the point where the said cable is secured to the mine. By means of this device it is possible to anchor the mine at depths varying from one 15 to the other of the distances which separate, on the circumference of the sounding-lead on which the cable is wound, the openings of two consecutive ducts. By utilizing a suitable number of the aforesaid ducts, 20 for instance, three or four in the case of sounding-leads of the usual size, the distance aforesaid may be sufficiently reduced in order that the length of the unwound cable should not differ from that intended by more than the quantity due to errors inherent to any anchorage of submarine 25 mines.

What I claim and desire to secure by Letters Patent of the United States is:

1. For use with submarine mines, a device 30 consisting of a sounding-lead having a plurality of preferably diametral ducts formed in and extending through the body thereof and a cable wound on said sounding-lead for connecting the latter with the 35 mine, adjustment of the length of said cable being effected by unwinding a length of the

cable corresponding to the depth of immersion increased by the length of the said ducts, the unwinding action being stopped by passing the free end of the unwound 40 length into the duct nearest thereto.

2. In combination, a submarine mine, a lead having a plurality of passages therein, and a cable carried by said lead for anchoring the mine at variable depths, the free 45 end of which cable passes through the passage nearest thereto and is connected to said mine.

3. In combination, a submarine mine, a lead having a plurality of passages therein, 50 and a cable carried by said lead for anchoring the mine at variable depths, the free end of which cable passes through the passage nearest thereto and is connected to said mine, said cable engaging said passage at 55 two points and holding the mine at a predetermined depth.

4. In combination, a submarine mine, a lead having a plurality of passages passing through the body thereof, and a cable carried by said lead for anchoring the mine at 60 variable depth, the free end of which cable passes through the passage nearest thereto and is attached to said mine to hold the same at a predetermined depth. 65

In testimony whereof I have signed this specification in the presence of two subscribing witnesses.

EUGÈNE SCHNEIDER.
